UNITED STATES PATENT OFFICE.

HARVEY L. WHEELER, OF FREMONT, OHIO.

DRIER.

Original application filed March 28, 1921, Serial No. 456,058. Divided and this application filed October 28, 1921. Serial No. 510,993.

To all whom it may concern:

Be it known that I, HARVEY L. WHEELER, a citizen of the United States, residing at Fremont, in the county of Sandusky and State of Ohio, have invented new and useful Improvements in Driers, of which the following is a specification.

This invention relates to driers particularly designed for use in connection with washing machines for drying clothes after they have been washed and rinsed.

An object of the invention is to provide a drier mechanism which utilizes centrifugal action for drying clothes eliminating the manual labor with the use of an ordinary wringer and also eliminating the liability of breaking or removing buttons from the clothes during wringing operation.

A further object of this invention is to provide a drier mechanism as specified which is comparatively simple in construction and one wherein the speed of the rotor may be regulated as desired as well as to provide a drier arranged so as to prevent accumulation of water therein and the resultant unsanitary conditions within the drier.

The present application is a divisional application of my application upon a washing machine filed March 28, 1921, Serial No. 456,058.

Other objects of the invention will appear in the following detailed description and in the accompanying drawing wherein:

Fig. 1 is a vertical section through the drier showing the operating mechanism therefor.

Fig. 2 is a horizontal section through the drier taken on the line 2—2 of Fig. 1.

Fig. 3 is a horizontal section taken on the line 3—3 of Fig. 1.

Referring more particularly to the drawing the improved drier mechanism is shown associated with a clothes washing mechanism 1 which specifically described in my copending application filed March 28, 1921, Serial No. 456,058, and after the clothes are thoroughly cleansed or washed by the washing machine structure they may be removed therefrom and placed in the container 35 of the drier structure. The container 35 is substantially cylindrical in shape and has its side walls perforated as shown at 36 while its upper end is open as shown at 38' to permit placing of the

clothes therein. It has a central sleeve 37 upturned at the center of its base through which the operating shaft 38 extends. The upper end of the sleeve 37 is flanged as at 39 and a binding block 40 is mounted thereon, the said block being connected to the shaft 38 by means of a threaded stud 41 and a rectangular portion 42 formed upon the shaft which engages in the central rectangular opening in the binding block 40. An imperforate sheet metal cone 43 is attached to the binding block 40 and to the upper surface of the bottom 44 of the container 35 and acts as a shed to guide the water outwardly for passage out of the container 35 through the perforations 36 during the rotary movement of the container. The shaft 38 has a friction pulley 45 mounted thereon adapted for coaction with a friction cone 46 for rotating the container 35. The friction cone 46 is feathered upon the drive shaft 53 and it is moved into and out of operative engagement with the friction pulley 45 by a lever 47. The lever 47 is connected to a shifting lever 48 which is positioned at one side of the bench or support 57 and is connected to the lever 47 by a link 49 and rod 50. When the clothes to be dried are placed within the container 35 and the same is rotated the centrifugal action of the rotating container and clothes therein throws off the water from the clothes which water passes out of the container through the openings 36 and is guided towards the drain 51 of the receptacle 58 by a suitable conical shed 52. The receptacle 58 is cylindrical in shape and is made of any suitable material such as galvanized iron, copper or the like. A suitable closure 59 is provided for the receptacle 58.

From the foregoing description taken in connection with the accompanying drawing and with my copending application heretofore referred to it will be apparent that after the clothes are thoroughly cleansed they may be rinsed either in the washing machine or removed therefrom and rinsed and placed in the container 35, or they may be rinsed after being placed in the container 35 by running clear water on the clothes in the container during rotation thereof which will cause thorough rinsing action of the clothes and after the clothes are rinsed the flow of water is cut off and

continued rotation of the container 35 will force the greater portion of the water out of the clothes by centrifugal action and eliminate the need of wringing the clothes.

5 While I have referred to my particular drier as applicable for use in connection with the type of washing machine disclosed in my accompanying application it is to be understood that the drier may be used 10 in connection with any approved type of washer or independent thereof as desired.

It is, of course, to be understood that the invention may be constructed in various other manners and the parts associated in 15 different relations and, therefore, I do not desire to be limited in any manner except as set forth in the claim hereunto appended.

Having thus described my invention what I claim is:

20 A clothes drier comprising a cylindrical

receptacle, a rotary perforated clothes container in said receptacle, said container having an open upper end, a bearing sleeve turned upwardly from the axis of the bottom of said clothes container, a driving shaft extending through said sleeve, a binding block resting upon the upper end of the sleeve and connected to said shaft, a substantially conical water shed connected at its apex to said binding block and the 25 perimeter of its base to said container, a second conical water shed having its apex mounted on the shaft beneath the clothes container and its perimeter connected to the bottom of the receptacle, a power shaft, and 30 means for establishing connection between said power and driving shafts.

35 In testimony whereof I affix my signature.

HARVEY L. WHEELER.
